CLAIM

U.S. PATENT DOCUMENTS

The ornamental design for a handpiece for dental use, as described and shown.

DESCRIPTION

- D. 262,737 * 1/1982 Meller D24/146
D. 355,971 * 2/1995 Meller D24/152
D. 419,843 2/2000 Saitoh D8/61
D. 427,039 6/2000 Ono D8/61
4,484,892 * 11/1984 Pernot et al. 433/131

FIG. 1 is a front elevation view of a handpiece for dental use, showing my claimed design;
FIG. 2 is a rear elevation view thereof;
FIG. 3 is a right side elevation view thereof;
FIG. 4 is a top plan view thereof; and,
FIG. 5 is a bottom base view thereof.
